UNITED STATES PATENT OFFICE.

HENRY L. SCOTT, OF PROVIDENCE, RHODE ISLAND.

TESTING-MACHINE.

1,184,034.

Specification of Letters Patent. Patented May 23, 1916.

Application filed January 9, 1915. Serial No. 1,460.

To all whom it may concern:

Be it known that I, HENRY L. SCOTT, a citizen of the United States, and resident of the city of Providence, in the county of Providence and State of Rhode Island, have invented certain new and useful Improvements in Testing-Machines, of which the following is a specification.

This invention relates to testing machines of the class designed more particularly for exhibiting the breaking tensile strength in pounds or other unit of measure of textiles or other materials.

The object of the invention is to provide means for applying a tension to the material to be tested, sufficient to break the same, and also to provide means whereby the cross section of the material may be reduced to a predetermined dimension during the strain applying operation, for the purpose of accurately obtaining its tensile strength.

With these and other objects in view, the invention consists of certain novel features of construction, as will be more fully described, and particularly pointed out in the appended claims.

In the accompanying drawings: Figure 1— is a side elevation partly in section show one form of testing machine to which my improved device is shown as being attached. Fig. 2— is a side elevation partly in section showing one form of severing device and a portion of the means whereby it may be attached to the tension applying machine. Fig. 3— is a perspective view showing the gripping jaws engaging opposite ends of the narrow strip of fabric and representing a strip as having been pulled apart also showing the severing device in position to operate upon a strip held between the jaws. Fig. 4— represents a strip of material with its opposite edges cut inward a predetermined depth.

The usual method of testing woven fabrics such as cloth, canvas and the like, is to strip the material into narrow widths, usually about one inch wide and then apply a strain to the strip sufficient to pull the fabric apart, but it is found that such a test is quite unsatisfactory, particularly with the heavier fabrics such as canvas, duck or the like, for the reason that in weaving, the warp threads are passed alternately over and under the weft threads and are thus formed in a wavy or sinuous line which

naturally takes up considerable of their length, and when such a fabric is placed under tension the first two or three threads at the opposite edges of the strip which are practically released by the severed filling threads, straighten out, and thus fail to support their proportion of the load, and therefore by this means a fair test of the strength of the one inch of fabric cannot possibly be obtained. To obviate this difficulty, I have provided a simple method or means whereby a strip of material is employed which is about twice the width of that desired for the actual breaking test. To this I apply a predetermined tension and then cut or otherwise sever and reduce the cross section of the material to a predetermined dimension, preferably by cutting the warp threads at the opposite edges, and then continue the application of the power until the strip is broken, the breaking strain being indicated on a graduated dial. By this means the weft threads are firmly held by the ends of the interwoven warp threads from raveling or straightening, thus the uncut warp threads of the full remaining inch will hold their original woven shape, and so take their full share of the load permitting an accurate test to be obtained of the fabric.

In the drawings I have illustrated one form of tension applying mechanism in which—

10 and 11 designate the opposite supports which are connected together by means of a plurality of tie rods 12, on the upper pair of which are supported longitudinal rails 13 on which roll the two carriages 15 and 16 on their respective wheels 17 and 18. The carriage 15 is connected by a chain 19 to the hub 20 which is mounted on suitable anti friction bearings in the head 21. To this hub is secured a pair of pendulum arms 22 and to the lower portions of these arms is secured an adjustable weight 23 by the screw 24. A gear segment 25 is also connected to this hub 20 to engage with the pinion 26 and so operate the pointer 27 to indicate in pounds or other unit of measure on a fixed graduated dial 28 the amount of tension which is being exerted on the material through the chain 19. On this carriage 15 is mounted a gripping jaw 29 which may be operated by the hand screw 30 and a duplicate jaw 31 is connected to the carriage 16, its loose jaw being pivoted at 32 and

operated by the hand screw 33. To the carriage 16 is connected a long tension screw 34 which passes through the head 35 in which is mounted suitable mechanism (not shown) whereby the rotating of the hand wheel 36 causes a longitudinal movement of said tension screw.

The feature of my present invention is the provision of means whereby the edges 10 of the material operated upon may be cut, or a portion of the stock removed from the edges thus reducing the effective cross section of the material to a predetermined dimension, and to accomplish this in a 15 simple and effective way, I have shown one form of mechanism which is that of a standard portion 37 which may be clamped by means of a screw 39 through the front bar 38 to the tie rods 12 and on this standard I have pivoted at 41 a cutter arm 40. This arm 40 is provided with a pair of blades 42 and 43 which are fastened thereto by screws 44 and 45 and in order to provide 20 a suitable support for the material while being cut, I have provided a rest arm 46 which is slotted at 47 and 48 to receive the blades 42 and 43 when the cutter arm descends to force these blades through opposite edges of the material. This arm 40 is 25 slotted longitudinally at 60 about the screws 44 and 45 to permit the knives to be adjusted toward and from each other, and so regulate the depth of this cut in the opposite edges of the material.

30 The operation of my improved mechanism is as follows:—The opposite ends of the material *a* to be tested are firmly gripped in the jaws 29 and 31 which are mounted on their respective carriages 15 and 16. At the 35 beginning of the test the weight 23 hangs vertically and the pointer 27 indicates zero, the strain is applied to the material by rotating the hand wheel 36 thereby moving both carriages to the right and swinging the weight from its vertical position and when the pointer indicates a predetermined amount the hand of the operator strikes the handle 49 of the knife arm and the blades 42 and 43 are forced down through the material severing the edges of the same inward a predetermined distance. These blades are 40 immediately returned by the spring 50 and the tension process is continued until the material breaks at which time the portion 45 of the pointer is accurately noted thus indicating the exact tension in pounds or other unit of measure at which the material was severed. The pendulum arm 22 is provided with a pawl 51 which contacts with the notched surface of the segment bar 52 so 50 that this weight and the pointer are caused to remain in their advanced position until such time that it is desired to return them to normal which may be accomplished by a 55 small reel 53 operated by the handle 54 to

wind up the cord 55 and apply sufficient tension on the arm 56 to release the pawl 51 and then lower the weight back to normal.

It will be noted in Fig. 2 that I have 60 formed the cutter knives of thin blades having their edges beveled at an angle lengthwise, with their inner edges the deepest, so that these edges will first pierce the fabric and then cut in opposite directions outward toward the adjacent edges thereof. In this 65 way lateral tension is applied which prevents the fabric from puckering or wrinkling thus insuring the most accurate results, but any suitable form of blades or method of cutting may be employed.

The broad idea of my present invention 70 is the provision of a strip of material wider than that to be tested and providing means for applying a tension to break the material and to reduce the cross section of the material to a predetermined dimension during 75 the strain applying operation and I have shown one form of mechanism for accomplishing this result but any mechanism adapted to perform this function will fall 80 within the spirit and scope of my invention.

I have described the testing strain on the fabric as being applied in the direction of its warp threads but the same test may be 85 made equally as well in the direction of the weft threads if desired.

I claim:

1. In a testing machine, means for applying tension to the material to be tested, a 100 cutter for making a slit in the edge of the material thereby reducing the same to a predetermined dimension to permit said tension applying means to break said reduced portion, and means in said machine for supporting and guiding said cutter.

2. In a testing machine, means for applying tension to the material to be tested, a plurality of cutting blades, cutters for making slits in opposite edges of the material 110 thereby reducing the same to a predetermined dimension to permit said tension applying means to break said reduced portion, and means carried by the machine for supporting and guiding said cutters.

3. In a testing machine, means for applying a tension to the material to be tested, a pair of spaced apart cutters for cutting slits in the edges of the material thereby reducing the same to a predetermined dimension 120 to permit said tension applying means to break said reduced portion, and a frame carried by the machine in which said cutters are mounted and guided.

4. In a testing machine, means for applying a gradual tension to break the material to be tested, a pair of cutting edges arranged to cut slits in opposite edges in the material for reducing the same in cross section to a predetermined dimension when a given ten- 125

- sion has been applied during the breaking operation, and means for guiding and controlling said edges.
5. In a testing machine, means for applying a tension to a strip of material sufficient to break the same, means comprising a pair of cutting edges to cut slits simultaneously in opposite edges of the strip thereby reducing the same simultaneously in opposite edges of the strip reducing the same to a predetermined testing width during the strain applying operation, and means for guiding and controlling said cutting edges.
6. In a testing machine, means for applying a tension on a strip of material, a pair of coöperating spaced apart cutters for slitting opposite edges of the strip and so reducing the same to a predetermined testing width during the strain applying operation, means for guiding the cutters, and means for supporting the material about the cutters during the cutting operation.
7. In a testing machine, means for applying a tension to a strip of material sufficient
- to break the same, a pair of coöperating 25 spaced apart blades for cutting a narrow slit in opposite edges of the strip, thereby reducing the same to a predetermined testing width during the strain applying operation said blades being arranged to cut into 30 the body of the fabric in a direction outward and toward its opposite edges.
8. In a testing machine, means for applying a tension to a strip of material sufficient to break the same, a pair of blades for cutting a narrow slit in opposite edges of the strip reducing the same to a predetermined testing width during the strain applying operation, and means whereby the knives may be adjusted to regulate the distance between 35 40 them.

In testimony whereof I affix my signature in presence of two witnesses.

HENRY L. SCOTT.
